DRIVING MECHANISM FOR LOOMS

Elbridge R. Holmes, Worcester, Mass., assignor to
 Crompton & Knowles Loom Works, Worcester,
 Mass., a corporation of Massachusetts

Application June 21, 1934, Serial No. 731,695

5 Claims. (Cl. 192—99)

This invention relates to improvements in driving or shipping mechanisms for looms and it is the general object of the invention to provide an improved mechanism of this kind which shall

5 permit the loom to be clutched to its driving motor with a minimum of effort on the part of the user.

In shipping mechanisms of certain types of looms as heretofore constructed the two clutch members on the driving shaft have been held together by a force which is exerted longitudinally of the shaft. With such an arrangement there results end pressure between the clutch controller and a stationary part of the loom which causes 15 rapid wear. It is an important object of my present invention to provide means for clutching the loom to its driver through mechanism which exerts a force transversely of the shaft between two parts which are carried by the shaft. In 20 this way the end thrust which is required to exert the transverse force can be reduced to a minimum.

It is a further object of my invention to provide a collar which is secured to the driving shaft 25 in adjusted position and to pivot to it a yoke or setting lever having parts to exert a force longitudinally of the shaft and cause engagement of the clutch elements and having other parts which are acted upon by a toggle connection to move 30 transversely of the shaft when a sliding collar on the shaft is moved by a shipper lever. The force which must be exerted between the driving and driven members of the clutch increases as they are pressed together and the effect of the 35 toggle is to exert an increasing force as the sliding collar moves along the shaft, thereby relieving the weaver of the necessity to pull with increasing force on the shipper handle as the loom starts to run.

40 It is another object of my present invention to make the previously mentioned collar which is fastened to the shaft adjustable longitudinally to compensate for wearing of the clutch elements and also for variation in the pressure of the 45 toggle.

It is a still further object of the invention to provide the previously mentioned sliding collar with a strap or pivot support which can be adjusted transversely of the shaft to vary one of the pivots of the toggle link and this adjustment 50 together with the one mentioned in connection with the collar which is fastened to the shaft affords means for giving the toggle connection a variety of settings.

55 With these and other objects in view which will

appear as the description proceeds, my invention resides in the combination and arrangement of parts hereinafter described and set forth in the claims.

In the accompanying drawing, wherein a convenient embodiment of my invention is set forth,

Fig. 1 is a front elevation, parts being in section, of the driving mechanism of a loom having my invention applied thereto,

Fig. 2 is a vertical section taken transversely 10 of the driving shaft on line 2—2 of Fig. 1,

Fig. 3 is a longitudinal section taken vertically 15 through the shaft along lines 3—3 of Fig. 2,

Fig. 4 is a diagrammatic view showing certain 20 parts of Fig. 1 in a different position, and

Fig. 5 is a vertical section on line 5—5, Fig. 1, 25 on a reduced scale.

Referring particularly to Fig. 1, the loom frame 10 supports a main bearing 11 for the top or 30 crank shaft 12. The latter drives a lay through 20 a connector 13 and may have one revolution for each pick of the loom. A top gear 14 is secured to the shaft and has bolted thereto at one side a 35 brake wheel 15 and at the other side a driven clutch element 16. The parts 14, 15 and 16 rotate with the shaft at all times, the gear 14 meshing with a lower gear of twice the size shown at 17 and the brake wheel 15 cooperating with brake mechanism not shown to stop the loom quickly should a shuttle be caught in the shed of the 40 warp.

Rotating loosely on the shaft 12 is a driving gear 20 which meshes with the driving pinion of a motor not shown. The driving gear has a web 21 having a friction face 22 against which the 45 friction material, such as cork or leather 23, of the driven clutch element presses. The gear in effect is the driving clutch element and is normally spaced from the driven element by means of compression springs one of which is indicated 50 at 24 in Fig. 1. These springs act on the hub 25 of the driving gear to press the latter away from the driven part of the clutch. The effect of these springs is to prevent dragging of the 55 clutch surfaces when the loom is at rest.

Extending laterally from the loom frame is a shipper bearing support 30 having a bearing 31 in alignment with the bearing 11 and through which the outer end of the shaft 12 extends. The bearing and stand are held rigidly in place 50 and support a pivot 32 around which a shipper lever 33 moves. As indicated in Fig. 5 the shipper lever is formed in two parts 34 and 35 which may have slots 36 through which the trunions 37 of a thrust collar 38 extend.

r a loom, a shaft to

The matter thus far described may be of usual form and of itself forms no part of my present invention. A movement of rod 39 to the left as viewed in Fig. 1 will move the shipper lever 33 to cause movement of the thrust collar 38 toward the clutch and driving gear for the purpose of causing loom operation, and when said rod is moved to the right the clutch elements are released and will be separated by the springs 24.

In carrying my present invention into effect I interpose between the shipper lever 33 and the driving gear a set of parts which convert the longitudinal movement of the shipper lever along shaft 12 first into a force transverse of the shaft and then back to a force longitudinal of the shaft, the transverse component being of considerable power so that comparatively slight force is required to be exerted on the shipper lever to drive the loom. A collar 50 is fixed in adjusted angular and longitudinal position on the shaft 12 to rotate with the latter by means of a set screw 51 and there is extending through said collar a pivot pin 52 which passes to one side of the shaft 12.

A setting yoke or lever 55 has spaced bearings 56 lying on opposite sides of the collar 50 and through which the pin 52 extends. These bearings are connected by a web 57 and the bearings have projecting therefrom arms 49 having thrust nose pieces 58. The latter bear against a pressure washer 59 which is in engagement with the right hand end of hub 25 as viewed in Fig. 1 and is renewable when worn. The washer 59 has projecting therefrom a pin 60 which enters the fixed collar 50 so that the washer 59 is held normally against rotation. This is shown more particularly in Fig. 4, but I do not wish to be limited to use of the pin 60 or washer, although the latter takes wear which would otherwise be caused on the hub 25 by the noses 58.

A sliding collar 65 is mounted to move freely along and angularly with respect to the shaft 12 and has fitted thereover a U-shaped strap or yoke 66 through which extends a set screw 67 which projects as shown in Fig. 2 into the collar 65. A second pivot pin 68 passes through the parallel sides 69 of the strap 66 and that portion of said pin 68 between the sides 69 lies in a slot 70 formed in the collar 65. By reason of the slot the pin is required to move in a radial direction only with respect to the collar 65 when adjustments are made by the set screw 67.

Loosely pivoted at each end of the pin 68 is a toggle link 75 and each toggle link in turn is pivoted as at 76 to an arm 77 projecting from the setting element 55 in a direction substantially longitudinally with respect to shaft 12. As shown in Fig. 3 the sliding collar 65 is slotted to receive the thrust collar 38 and the latter is C-shaped so that it may be fitted between the shoulders 78 defined by the groove 79 in collar 65 into which collar 38 fits.

In operation, with the loom idle, the parts will be in the position shown in Fig. 1 with the driven and driving clutch elements separated. Shipper lever 33 tends to move to the right by yielding means not shown but old, and the arms

to move collar 65 longitudinally viewed particularly in Fig. 1 will cause the links 75 to 68 and assume positions parallel to the axis of the shaft as viewed of the latter. The pins 51 move toward the center of the shaft or upwardly and setting lever 55 around pin 51 in a clockwise direction as viewed in Fig. 1. Noses 58 longitudinally of shaft 59. When the shipper lever 32 is moved to its full position the partition indicated diagrammatically by the pivots 68 and 76 is in a position perpendicular to the axis of the shaft in a stable condition and can be held in this position with slight holding force on handle 33, which is yieldingly located on the handle, not shown, but which is copending application file No. 731,073 filed June 18, 1948. The members are in the position indicated when the members are in tight engagement and driving force will be communicated through gear 20 to the shaft 12.

To unship the loom, lever the right to cause movement the shaft and the links 75 to cause pivots 76 to move c the axis of the shaft as view moving the noses 58 away f to permit separation of the

If an adjustment of the screw 51 may be loosened at either angularly or longitudinally. A further adjustment may be made on screw 67 so that the pivot is toward or from the axis of the clutch elements and washer and extent of clutching.

From the foregoing it will provided a simple means for c elements of a loom by mean nism which can be operated amount of force exerted on r nism includes a toggle conn which increases as the collar the driving gear and since t panies an increase in the p driving and driven clutch ele no objectionable increase in t be exerted on rod 39 to effec of the clutch devices to drivi also be seen that the collar 50 ing strap or yoke 66 permit toggle connection both longit versely of the shaft.

Having thus described my seen that changes and modifi- therein by those skilled in t parting from the spirit and iation and I do not wish to be li herein disclosed, but only to

1. In driving mechanism for

transversely of the shaft, a link transverse of the shaft connected to the second arm and the other collar, relative movement of the collar causing movement of the second arm transversely of the shaft to effect driving relation between the clutch elements, and a pivotal support for the link on one of the collars movable to any one of a plurality of fixed positions transversely of the shaft.

5. In driving mechanism for a loom, a shaft to be driven, a pair of clutch elements movable relatively to each other one of which moves with the shaft at all times and the other of which is loose on the shaft, a collar fastened to the shaft, a setting lever pivoted to the collar and having an arm part of which is movable longitudinally with respect to the collar into engagement with the element loose on the shaft, a second collar loose on the shaft but movable longitudinally along the shaft, a yoke carried by the second collar and capable of assuming a plurality of positions relatively to the second collar and transversely of the shaft, a link one end of which is pivotally supported by the yoke and the other end of which is connected to the setting lever, movement of the second collar longitudinally of the shaft causing relative movement between the link and setting lever to effect rocking of the latter in a direction to move the said arm of the setting lever into engagement with the loose element to move the latter into operative relation with respect to the other element.

6. In driving mechanism for a loom, a shaft to be driven, a driven element fixed to the shaft, a driving element loose on the shaft, a collar fixed to the shaft, a setting lever pivoted to the collar and having an arm extending transversely of the shaft and positioned for engagement with the second named element, the setting lever having a second arm extending longitudinally of the shaft, a second collar loose on and slideable longitudinally along the shaft, a yoke carried by the second collar, means to give the yoke a plurality of positions relatively to the second collar and transversely of the shaft, a link pivotally mounted to the yoke and normally oblique with respect to the axis of the shaft, a pivotal connection between the setting lever and the link, and means to move the collar longitudinally along the shaft, movement of the sliding collar longitudinally of the shaft causing the link to assume a position approximately perpendicular to the shaft and effecting rocking of the setting lever to move the first named arm of said setting lever into operative relation with respect to the

loose element and move the latter against the element tight on the shaft, the degree of force exerted by the first named arm of the setting lever on the loose element varying with the transverse setting of the yoke relatively to the shaft.

5

4. In driving mechanism for a loom, a shaft to be driven, a pair of clutch elements movable relatively to each other and one of which moves with the shaft, a sliding collar on the shaft, a fixed collar on the shaft, a setting lever pivoted to the fixed collar and having an arm part of which is normally in non-pressure-transmitting relation with respect to the elements but movable longitudinally of the shaft into engagement with one of the elements to operatively relate the clutch elements and having another arm part of which is movable transversely of the shaft, a toggle link extending transversely of the shaft and interposed between the sliding collar and the second named arm of the setting lever to cause rocking movement of the latter when the sliding collar moves longitudinally of the shaft, and means carried by and restrained against movements longitudinally of the shaft relatively to the sliding collar by the latter and pivotally connected to the link and movable relatively to the sliding collar transversely of the shaft to vary the position of the link transversely of the shaft.

25

5. In driving mechanism for a loom, a shaft to be driven, a pair of clutch elements movable relatively to each other and one of which moves with the shaft, the other element being movable along the shaft to have driving relation with the first element, a setting lever, means rigid with the shaft defining a pivotal connection for the setting lever, said lever having two arms a part of one of which moves longitudinally of the shaft when in engagement with said other element to effect driving relation between the elements and the other arm of which has a part movable transversely of the shaft, a collar slideable on the shaft, spaced walls on the collar defining guides extending transversely of the shaft, a strap between the walls and held by the latter against relative movement with respect to the sliding collar in a direction longitudinally of the shaft, adjustable means interposed between the strap and the sliding collar to vary the transverse setting of the strap relatively to the shaft, and a toggle link pivotally connected to the strap and also to the second named arm of the setting lever.

ELBRIDGE R. HOLMES.
